OF DELAWARE.

PRINTING TELEGRAPHY.

Application filed September 2, 1922, Serial No. 585,871. Renewed March 31, 1927.

In the transmission of messages by printing telegraphs, employing the Baudot or any other code, it has become desirable to provide means for the transmission and reception of auxiliary signals, including service signals, such as "start", "stop", "re-run", "re-punch", etc., which are not sent by means of perforated tape or keyboard, but on account of their frequent recurrence, are transmitted by special code wheels, or similar means, and received on audible devices, such as bells, or otherwise.

One form of sending devices of this character is shown in U. S. Letters Patent No. 1,275,559, and another in application for U. S. Letters Patent, Serial No. 504,862, filed October 3, 1921. These devices are intermittently operated, and provide for the interruption of the regular message and of the operation of the tape feeding mechanism at the sending station, while service or auxiliary signals are sent.

The present invention relates to a receiving unit of a printing telegraph system, and an audible signal, such as a bell therein, which invariably will be operated after a blank signal is received from the sending unit. The usual start impulse operates a control relay having two contacts, one of which, in conjunction with the spacing contact-point of the line relay, closes a locking circuit for the control relay, while the other contact, when the control relay is deenergized, short-circuits the signal bell magnet of the receiving unit and prevents the bell from ringing.

The drawing discloses a diagrammatic view of a part of the receiving unit used in the reception of audible auxiliary signals, in which 10 indicates a transmitting station connected by means of main line 11 to polarized line relay 12 of a receiving station. Contact tongue 13 plays between spacing contact point 14 and marking contact point 15. Conductor 16 leads to control relay 17 while a second conductor 18 connects control relay 17 with start magnet 19 and, by means of conductor 20, with start segment 21 of distributor head 22. Brush arm 23 travels in the usual manner over the face of distributor head 22 and the brushes on brush arm 23 connect the outer segmented ring of the distribu-

tor head to battery ring 24. The latter is connected by means of conductor 25 to positive pole of battery 26. Conductor 27 leads from negative pole of battery 26 to contact tongue 13 of line relay 12.

Control relay 17 is provided with two contacts, preferably on one and the same armature, 28 and 29, one of which, contact 28, is arranged to close locking contact point 30 and connect one winding of relay 17 over conductors 31 and 25 to positive pole of battery 26. A second conductor 32, containing a suitable resistance leads to spacing contact point 14 of line relay 12.

The selector unit contains selector magnets 33, 34, 35, 36 and 37, connected as now known in the art, to segments 1, 2, 3, 4 and 5, of distributor head 22. Common conductor 38 connects the selector magnets over a resistance and conductor 16 to marking contact point 15 of line relay 12. The negative pole of battery 26 is connected, by means of conductor 40, to sixth impulse magnet 41, and out-going conductor 42 thereof leads to wire joint 43 and, by means of conductor 44, to magnet 45 of signal bell 46, while a second conductor 47 connects the out-going terminal of bell magnet 45, over wire joint 48 and conductor 49, to the sixth impulse segment 6 of distributor head 22.

Contact 29 of control relay 17, when the latter is deenergized, closes contact point 50, thereby short-circuiting signal bell magnet 45. A resistance 51 is placed across conductors 16 and 18, so as to make the right hand winding of control relay 17, slow to release, when its circuit is opened at contact tongue 13, in passing from marking contact 15 to spacing contact 14.

Operation.

The drawing indicates that contact tongue 13 of line relay 12 is normally in contact with spacing contact point 14. When the start impulse is now received, tongue 13 moves over to marking contact point 15 and energizes control relay 17 over the following circuit: negative pole of battery 26, conductor 27, contact tongue 13, contact point 15, conductor 16, right hand winding of control relay 17, conductor 18, winding of start magnet 19, conductor 20, start segment 21, of

distributor head 22, brush arm 23, battery ring 24, and, over conductor 25, back to positive pole of battery 26. The effect of the closing of this circuit is the energization of control relay 17 and start magnet 19. Start magnet 19, when energized, releases brush arm 23, which begins to rotate over the face of distributor head 22. If now the start impulse received from transmitting station 10 is followed by a blank signal, containing, for instance, five spacing impulses, relay tongue 13 will move back against its spacing contact 14, brush arm 23 continues its rotation to sixth impulse segment 6, control relay 17 will be locked up at its contact point 30 and spacing contact point 14, and when this condition prevails, bell magnet 45 is in series with sixth impulse magnet 41 and, assuming brush arm 23 reaches sixth impulse 15 segment 6, then bell 46 will ring. If, however, any one or more of the selecting impulses are of marking polarity and energizing one or more of selector magnets 33 to 37, inclusive, relay tongue 13 of line relay 12 20 will move over to marking contact point 15, the locking circuit for control relay 17, is opened at spacing contact point 14 and locking contact point 30 of control relay 17, and control relay 17 will again be deenergized. 25

It will be seen that when brush arm 23 passes sixth impulse segment 6, while control relay 17 is deenergized, contact 29 of control relay 17 closes contact point 50, bell magnet 45 will thereupon be short-circuited and bell 46 will 30 not ring.

As invention is claimed:—

1. In combination, signaling mechanism for printing telegraphs comprising a line relay and a signal distributor, a start magnet and a control relay controlled by said line relay, a circuit controlled by said control relay, a sixth impulse magnet and a signal magnet in said circuit, and means controlled by said distributor and said control relay 40 for preventing operation of said signal magnet and permitting operation of said sixth impulse magnet.

2. In combination, a receiver selectively responsive to code combinations of marking and spacing conditions, distributing means controlling said receiver and initiated in operation by a start condition preceding each code combination of conditions, and special signaling means operated by a code combination of like conditions preceded by a start condition.

3. The combination as set forth in claim 2 in which said code combination of like conditions comprises all spacing conditions.

4. The combination as set forth in claim 2 in which said distributing means comprises a rotary start-stop distributor, and said receiver comprises a printing telegraph machine.

5. The combination as set forth in claim 2

in together with means controlled by said distributing means for causing operation of said receiver after the reception of said code combination of marking and spacing conditions.

6. In combination, a telegraph printer selectively responsive to code combinations of marking and spacing conditions; a rotary distributor controlling said printer and initiated in operation by a start condition 70 preceding each code combination of conditions; means controlled by said distributor for causing operation of said printer after the reception of a code combination of marking and spacing conditions; special signalling means operated by a code combination of spacing conditions preceded by a start condition; and means for preventing operation of said special signalling means when the printer is operated.

7. The combination as set forth in claim 6 in which said printer operating means comprises a sixth pulse magnet, and said special signal means comprises a signal operating magnet in series with said sixth pulse magnet.

8. The combination as set forth in claim 6 in which said printer operating means comprises a sixth pulse magnet, and said special signal means comprises a signal operating magnet in series with said sixth pulse magnet; together with means for preventing operation of said special signalling means comprising a relay for short-circuiting said signal operating magnet.

9. The combination as set forth in claim 6 in which said printer operating means comprises a sixth pulse magnet, and said special signalling means comprises a signal operating magnet in series with said sixth pulse magnet; together with means for operating said signalling means comprising a relay for short-circuiting said operating magnet and a locking circuit for said relay controlled by said start conditions and said code combinations of conditions.

10. In a printing telegraph receiver, a plurality of receiver magnets, a signalling device and a circuit for operating said signalling device, said circuit being completed only when none of said receiver magnets are operated.

11. In a printing telegraph receiver, a plurality of receiver magnets selectively operated in response to received code combinations of impulses, a special signalling device, and a circuit therefore completed when none of said receiver magnets are operated.

12. In a printing telegraph receiver, a plurality of receiver magnets selectively responsive to received code combinations of marking impulses, a signalling device, a circuit therefore, said circuit being completed in response to a code combination of spacing impulse.

13. In a printing telegraph receiver, a plurality of receiver magnets selectively responsive to code combinations of impulses, of a pre-determined character, a signalling device and a circuit therefore selectively responsive to a code combination of impulses of a character different from that to which said receiver magnets operate. 70
14. In a printing telegraph receiver, a signalling device, a circuit for operating said signalling device, means responsive to an impulse of a pre-determined character to condition said circuit to operate said signalling device and means for completing said circuit for operating said signalling device, said means being effective only in response to a code combination of impulses of a pre-determined character. 75
15. In a printing telegraph receiver, a signalling device, means responsive to a received impulse of a pre-determined character for conditioning said signalling device for operation, means responsive to received impulses of the same character for maintaining said condition, and means responsive to a further impulse of the same character for completing said condition to operate said signalling device. 80
16. In a printing telegraph receiver, a signalling device, a circuit therefore, means responsive to an impulse of a pre-determined character for conditioning said circuit to operate said signalling device, means responsive to an impulse of a pre-determined character for maintaining said circuit condition, and means responsive to a predetermined impulse of predetermined character for completing said conditioned circuit to operate said signalling device. 85
17. In a printing telegraph receiver, a plurality of selector magnets selectively responsive to received code combinations of impulses, a signalling device, a circuit therefore, means responsive to the first code impulse for conditioning said circuit, means for maintaining said condition as long as said receiver magnets remain non-operative and means operative if none of said receiver magnets are operated by the received code combination of impulses for completing said circuit to operate said signalling device. 90
18. In a printing telegraph receiver, a signalling device, a circuit therefore, a plurality of receiver magnets selectively responsive to received code combinations of impulses, means responsive to the first code impulse for conditioning said signalling device, circuit means responsive to received impulses of a character which do not operate said receiver magnets for maintaining said signalling device circuit, and means responsive to a received impulse of a predetermined character for completing said prepared circuit to operate said signalling device. 95
19. The method of operating a special signalling device which comprises preparing an electrical circuit therefore in response to an impulse of a pre-determined character, maintaining the prepared circuit as long as the impulses continue to be of pre-determined character, and completing the prepared circuit if the last impulse of the received code combination of impulses is of a predetermined character. 100
20. The method of operating a special signalling device which comprises preparing a circuit therefore in response to an impulse of pre-determined character and conditioning the maintenance of said circuit upon the character of the received code combination of impulses. 105
21. The method of operating a special signalling device which comprises conditioning the device for operation in response to an impulse of a pre-determined character and 85 conditioning the continued maintenance of said condition upon the receipt of a predetermined code combination of impulses and operating the signalling device upon the receipt of the last impulse of a pre-determined character. 90
22. The method of operating a signalling device which comprises conditioning said device for operation, maintaining said condition dependent upon the non-operation of a receiver, and thereafter completing the condition to operate the signalling device. 95
23. In a printing telegraph receiver, a distributor, a signalling device, means responsive to a received start impulse for starting said distributor into operation and simultaneously conditioning said signalling device for operation, means responsive to an impulse of predetermined character for maintaining said signalling device condition and means including said distributor responsive to an impulse of pre-determined character for completing said condition to operate said signalling device. 100
24. In a printing telegraph receiver, a signalling device, a circuit therefore, means responsive to start impulse for starting said distributor into operation and for simultaneously conditioning said circuit, means responsive to impulses of a pre-determined character for maintaining said condition, and means including said distributor for completing said prepared circuit to operate said signalling device. 105
25. In a printing telegraph receiver, a signalling device, a plurality of receiver magnets, a distributor, means responsive to an impulse for simultaneously starting said distributor into operation and for conditioning said signalling device for operation, means including said distributor responsive to received code combinations of impulses for either maintaining the prepared condition of said signalling device or operating said receiver magnets and means including said 110
- 120
- 125
- 130

distributor for effecting the operation of said signalling means if its prepared condition has been maintained.

26. In a printing telegraph receiver, a signalling device, a circuit therefor, a plurality of receiver magnets, means for conditioning said signalling device circuit, means responsive to a received code combination of impulses for either maintaining said condition or for operating said receiver magnets, said signalling device being rendered non-operative if a received impulse fails to maintain its condition.

27. In a printing telegraph receiver, a signalling device normally in a non-operating condition, means responsive to a start impulse for conditioning said signalling device for operation, a plurality of receiver magnets and means responsive to a code combination of impulses for either maintaining said sig-

nalling device in condition for operation or operating said receiver magnets.

28. In a printing telegraph receiver, a signalling device normally in a non-operative condition, means responsive to an impulse for conditioning said signalling device for operation, a plurality of receiver magnets, means responsive to a code combination of impulses for either maintaining said signalling device in condition for operation or operating said receiver magnets and means for effecting the operation of said signalling device if it has been maintained in condition for operation during the period of receiving the code combination of impulses.

Signed at Long Island City, in the county of Queens and State of New York, this 30 day of August, 1922.

ALBERT H. REIBER.
